ANIMATION DEVICE FOR MAKING ANIMATED FILMS AND THE LIKE

Kingdon S. Tyler, Silver Spring, Md., assignor to Vitro Corporation of America, New York, N.Y.

Filed Mar. 12, 1962, Ser. No. 181,223

4 Claims. (Cl. 352—87)

This invention relates to animation effects devices by means of which motions can be imparted to strips or tapes bearing ornamental or decorative material or indicia in relation to a subject, such as a picture, model or the like, to facilitate the production of animated films and the like.

This is a continuation-in-part of my co-pending application Serial No. 836,769, now abandoned, filed August 28, 1959, for "Animation Device For Making Animated Films And The Like."

Heretofore, in the production of animated films, it has been necessary to provide large numbers of drawings each slightly different from the other and which are photographed in succession in a step by step operation to produce a motion picture film. The operations are somewhat simplified by the use of transparent overlays or fixed backgrounds but even with these, the production of an animated film is complex, time consuming and correspondingly expensive.

In accordance with the present invention, an animation effects device is provided which can be used to impart motion to elements of a photographic setup so that the entire assembly can be photographed directly by a conventional motion picture camera to give the desired effect.

More particularly, in accordance with the invention, the new animation effects device includes a support for a picture, model, or the like and one or more mechanisms supported adjacent thereto by means of which belts or tapes may be moved relative to the picture or model to thereby indicate the movement of elements or the flow of materials, information, signals or the like which are to be represented in the filmed animation. The devices for moving the belts or tapes are constructed and arranged so that belts may be simultaneously driven thereby in different directions and at angles thereto in order to follow a continuous or angularly formed path as may be required. In this way, it is possible to do away with the expensive overlays and numerous drawings or photographs required in some types of animated films.

For a better understanding of the present invention, reference may be had to the accompanying drawings in which:

FIGURE 1 is a view in front elevation of a typical animation effects device embodying the present invention with a drawing mounted thereon;

FIGURE 2 is a rear elevational view of the animation effects device; and

FIGURE 3 is a rear elevational view of a modified form of the device illustrating a different mounting means for the animating devices thereof.

As illustrated in FIGURE 1, a typical device embodying the invention may include a frame member 10 of square or rectangular shape formed of wood, metal or the like, the frame being supported by means of pivot shafts 11 and 12 between the uprights 13 and 14 of a support similar to a blackboard support. Wingnuts may be threaded on the shafts 11 and 12 to enable the frame 10 to be locked in a vertical, horizontal or other angular position. The frame 10 serves to support a photograph, drawing, model or the like which is to form the background or base for an animated effect. As shown in FIGURE 1, a picture P of a ship S is mounted on the frame 10. Assuming that the animation is to indicate the flow of information, for example from the ship control

2

station C of the ship to a radar room T thereof, portions of the picture are cut away to form slots 15a to 15f shown in FIGURE 1. Movement of information from control station C to radar room T is indicated by an elongated flexible member such as symbol bearing belts or clear plastic tapes 16, 17 and 18 which respectively pass through the slots 15a, 15b; 15c, 15d; and 15e, 15f. The belts or tapes 16, 17 and 18 are supported on and driven by devices now to be described. Symbols carried by the tapes may be representative of electrical current, hydraulic fluid, aircraft, missiles, torpedos or any desired information.

Referring to FIGURE 2, the devices 19, 19' for moving the tapes or belts include rectangular frame members 20 and 21 which are carried by the angle irons 22 and 23 or the like mounted on the back of the frame 10. The angle irons 22 and 23 are provided with a series of holes 24 and 25 at each end enabling them to be adjusted endwise with respect to the frame or turned at a 90° or other angle with respect to the position shown as may be required. Inasmuch as the animation effects devices 19 and 19' are essentially the same, only one of them will be described. Thus, in the device 19 the frame 20 is provided with a pair of spools 26 and 27 over which the belt 18 is looped or on which a tape is wound. The spool 26 has a shaft 28 therein which extends between the side members 29 and 30 of the frame 20 and is provided with a manually operated crank 31 at one end so that the spool can be rotated. Similarly, the spool 27 includes a shaft 32 having a crank 33 on one end of it to enable the spool to be rotated. A bevel gear 34 is mounted on the right hand end of the shaft 32 and meshes with a bevel gear 35 on the end of a shaft 36 which also carries a spool 37 over which a belt or tape of film can be passed or wound. The shaft 36 is rotatably mounted in a U-shaped bracket 38 on the side member 30 of the frame 20.

The animation effects device 19' is also provided with a spool 40 which cooperates with the spool 37 to wind or unwind the tape or, in the case an endless belt is used, to support the belt with one of its flights extending through the slots 15c and 15d as shown. In this way, for example, by turning the crank 33, a tape which is wound on the spool 40 or a belt which passes around the spools 37 and 40 is driven with the result that the spool 40 turns and in turn drives the spools 27' and 26' moving the belt or tape supported by these spools. Also, rotation of the crank 33 drives the spools 26 and 27 and causes the belts or tapes supported by them to be driven endwise.

Action may be initiated with a leader of clear plastic tape exposed on the surface of the drawing or picture subject. The portion of the tape with printed or painted symbols appears first at control station C, upon spool rotation, from which point the symbols move down and across the picture subject and then up to radar room T. The resulting animation effects are continuous and may be photographed by a standard motion picture camera.

It will thus be apparent that a series of tapes or belts bearing indicia, designs, ornamentation or data can be driven simultaneously and displayed by passing the tapes through slots 15a to 15f in the picture P to illustrate or demonstrate the flow of information or the like from one area of the picture to another. Numerous other effects can also be achieved by changing the relation of the animating devices relative to the support and the model or picture carried thereby.

By changing the angles of the animation devices with respect to the frame, a different pattern such as zig-zag pattern, inverted U, Z patterns and the like can be achieved. Thus, for example, as shown in FIGURE 3, animation effects devices 45 and 46 like those described above may be mounted on pantographs 47 and 48 so that

they can be moved to almost any desired position with respect to the support 10'. Also the angular relation of the effects devices 45 and 46 can be modified by providing adjustable pivot supports 50 and 51 for connecting the devices to the arms of the pantographs. Likewise as shown in FIGURE 3, the drive mechanisms for the spools may be modified somewhat. For example, a crank 52 may be mounted on the shaft which supports a spool 53 by means of which the tape or belt extending between the devices 45 and 46 is supported. This crank may be connected by means of bevel gears 54 and 55 to one of the pair of parallel spools mounted within the frame of the device. Three additional spools and their associated belts or tapes on the device 46 may be similarly connected up.

Also, while the tape or belt supporting devices as shown are manually operated, it will be understood that they may be driven by electric motors, clock spring motors or the like and that more than two of the devices may be provided for use in conjunction with each model when a plurality of actions are to be shown simultaneously.

Accordingly, it will be understood that the forms of the invention as described herein are illustrative and that the invention is limited only by the terms of the following claims.

I claim:

1. Apparatus for use in making films using animation effects relative to a subject to be filmed comprising a support for mounting the subject to be filmed, at least one mechanism mounted behind said support for providing when actuated the animation effects, a pair of spools mounted in spaced relation in said mechanism, the subject to be filmed having openings corresponding to the spools, an elongated flexible symbol bearing member carried by the spools and extending through the openings, and means continuously to rotate the spools which actuates the mechanism and moves the symbol bearing flexible member in front of the subject to provide animation effects that may be continuously photographed by a motion picture camera.

2. Apparatus as defined in claim 1, in which means are provided to support the spool carrying mechanism for movement to different positions relative to the support.

3. Apparatus as defined in claim 1, including at least a second mechanism mounted behind the support and subject, a second pair of spools mounted in spaced relation in said second mechanism, openings in the subject to be filmed corresponding to the second pair of spools, an elongated flexible symbol bearing member carried by the second pair of spools and extending through the openings corresponding to the second pair of spools, a third pair of spools rotatably carried by said first and second mechanisms, means coupling at least one of the third spools to one spool of the corresponding first and second pairs of spools, a further elongated flexible symbol bearing member carried by the third spools and extending through corresponding openings in the subject to be filmed, and means to rotate one spool of said first, second and third pairs of spools to provide movement of the elongated flexible symbol bearing members between the pairs of spools.

4. Apparatus as defined in claim 3, wherein the flexible member extending between one of the pairs of spools is used as a power belt to drive one of the spools of another pair of spools.
